UNITED STATES PATENT OFFICE.

WILLIAM L. EGRY, OF DAYTON, OHIO, ASSIGNOR TO THE EGRY AUTOGRAPHIC REGISTER COMPANY, OF SAME PLACE.

AUTOGRAPHIC REGISTER.

SPECIFICATION forming part of Letters Patent No. 563,849, dated July 14, 1896.

Application filed April 27, 1894. Serial No. 509,232. (No model.)

To all whom it may concern:

Be it known that I, WILLIAM L. EGRY, of Dayton, Montgomery county, Ohio, have invented certain new and useful Improvements 5 in Autographic Registers, of which the following is a specification.

This invention pertains to improvements in devices for the storing of written records, such devices being generally known as "autographic registers."

My improvements will be readily understood from the following description, taken in connection with the accompanying drawings, in which—

15 Figure 1 is a vertical longitudinal section of an autographic register exemplifying my invention; Fig. 2, a sectional plan thereof; Fig. 3, a plan of the register; Fig. 4, a face view of the rammer; Fig. 5, a side elevation 20 of the rammer and its actuating mechanism; Fig. 6, a side elevation of the gripper and its actuating mechanism; Fig. 7, a plan of one 25 of the darts on which the paper is stabbed, and Fig. 8 a vertical longitudinal section of one of the spindles for the roll of paper.

In the drawings, referring in most instances to Fig. 1, 1 indicates the usual inclosing casing of an autographic register; 2, the tablet at the top thereof, over which the paper 30 passes to be written upon; 3, the wicket in the top of the casing to expose the paper upon the tablet; 4, the feed-rolls for carrying the paper forward; 5, the crank for operating the feed-rolls; 6, a roll of paper on a spindle 35 within the casing, this paper being hereinafter spoken of as the "bill-paper" to distinguish it from a second paper which contains the duplicate or record and goes on storage with the apparatus; 7, the bill-paper on its 40 way from the roll over the tablet and through the feed-rolls and then out of the apparatus, where it is torn off section by section, as used, this bill-paper being somewhat wider than the wicket 3, so that the edges of the paper will run 45 under the side margins of the wicket and thus be held down or prevented from being raised from the tablet; 8, the roll of record-paper; 9, the record-paper on its way from its roll, over the tablet and through the feed-rolls, and then 50 to a storage-compartment beyond the feed-rolls, this record-paper being somewhat wider

than the bill-paper, the two papers therefore lying together upon the tablet, it being understood that the usual carbon or transfer paper will be interposed between them; 10, folds of 55 the record-paper in the storage-compartment stabbed upon darts; 11, darts removably secured in the end door of the apparatus to receive the folds of record-paper, these darts being removably inserted in sockets in the end 60 door, so that a pile of the folds of paper may be removed, the darts coming along with the pile; 12, the end door of the apparatus, supporting the darts inclosing the storage-compartment, and capable of being turned down 65 so that the pile of record-paper can be gotten at; 13, Fig. 8, one of the spindles employed for the paper-rolls, the same being adapted to enter the axial hole in the roll of paper or the bore in the spool in case the roll is upon 70 the spool or reel; 14, end journals, capable of endwise movement in sockets in the ends of the spindle; 15, springs in the journal-sockets, urging these end journals outwardly, the journals having stop-pins to limit their outward movement, these stop-pins working in 75 slots in the spindles; 16, a flange mounted near one end of the spindle and capable of endwise motion thereon; 17, a spring urging the flange inwardly, this spring abutting against the 80 fixed flange on the end of the spindle; 18, Fig. 2, vertically-open bearings in one of the side walls of the casing, one of the journals 14 of the spindle resting in the appropriate one of these bearings, the end of the roll of paper 85 coming against the face of the bearing, while the other end journal of the spindle rests in a similar bearing upon the opposite wall of the casing, the spring 17 at that end of the spindle urging the flange 16 against the end of 90 the roll of paper, the arrangement being obviously such that the roll of paper is clamped with some force between the flange 16 and the bearing 18, whereby tensional resistance is maintained upon the roll as the paper is 95 drawn from it, the end journals of the spindle being urged outwardly against the side walls of the casing by the spring 15, whereby the spindle is elastically held in its bearings; 19, a shaft journaled in the casing; 20, a folding-rod disposed across over the record-paper between the feed-rolls and the darts on which 100

the paper is to be stabbed; 21, a pivoted arm carrying this folding-rod and serving to carry the rod up and down in producing the folds; 22, a pivoted lever having a pin in its long arm engaging under the arm 21 and having a pin in its short arm to be engaged by a cam on shaft 19; 23, a fixed support for the pivot of lever 22; 24, a volute cam on shaft 19, this cam engaging the pin in the short arm of lever 22, the arrangement being obviously such that as the cam 24 rotates in the direction of the arrow it will lift lever 22, and consequently lift arm 21 and elevate the folding-rod 20, and that when the offset in the cam 15 reaches the pin in lever 22 the previously elevated parts will be at liberty to fall by their own gravity, thus allowing folding-rod 20 to descend and carry down a fold of the record-paper in front of the darts in position 20 to be stabbed upon the darts, the folding-rod rising again to upper position before the stabbing takes place; 25, a pair of spring gripper-fingers near one wall of the casing in position to grip the lower end of the fold of paper 25 which has been carried down by the folding-rod 20, one of these fingers being stationary and the other being movable, so that the gripper may open and close; 26, Fig. 6, a lever having one end in engagement with the 30 movable gripper-finger and having the other end provided with a pin to be engaged by a cam on the shaft 19; 27, a fixed support for the pivot of this lever; 28, a cam on shaft 19, engaging the pin in lever 26, this cam being partly volute and partly concentric; 29, a spring tending to close the gripper 25, the general gripper arrangement being obviously such that the cam 28 will force the gripper open and hold it open until the offset in the 35 cam reaches the pin which it engages, whereupon the gripper will spring shut and clamp upon the fold of paper which has been carried down by folding-rod 20, cams 24 and 28 being so timed that the gripper will be held 40 open a proper time to receive the fold of the paper as the folding-rod 20 brings the fold down, and close upon the fold when the folding-rod rises; 30, a rammer-plate disposed in front of the darts and far enough from them 45 to permit the folding-rod to carry the fold of paper down between the rammer-plate and the ends of the darts, this rammer-plate being pierced for the darts, as seen in Fig. 4; 31, a guide to support the rammer-plate and 50 permit it to reciprocate to and from the paper stabbed upon the darts; 32, (see Fig. 5,) a lever having one arm linked to the rammer-plate, this lever being pivoted upon a fixed support; 33, a spring tending to rock the lever 55 32 and urge the rammer-plate toward and upon the darts; 34, a cam fast upon the shaft 19 and having a peripheral side rim, this cam having a concentric portion and an extension-elbow and an abrupt offset or jumping-off 60 65 place leading from the concentric portion to the extension; 35, a pin in the guide-stud of the rammer, this pin engaging within the rim

of cam 34, the general rammer engagement being obviously such that as cam 34 turns it will hold the rammer-plate back and then suddenly release it and allow spring 33 to force the rammer-plate forward toward and upon the darts, the cams being so timed with reference to each other that the fold of paper will be carried down by the folding-rod and the fold then grasped by the gripper, and the folding-rod will then rise and the rammer-plate then move forward and stab the fold of paper upon the darts, the gripper at the same time releasing the paper, the rammer-plate then retreating and the gripper opening ready for the folding-rod to carry down a new fold; 36, gearing connecting the feed-rolls with shaft 19, so that each folding and stabbing operation will correspond with such degree of 85 turning of the feed-rolls as is appropriate for the amount of record-paper required to form a fold; 37, a stop-pawl to prevent retrograde motion of the mechanism; 38, Fig. 3, a line printed across the upper or bill paper at the 90 end of each bill, the distance between these lines upon the paper therefore representing the length of the bill, a similar line being printed upon the record-paper in case the record-paper contains printed forms instead of 95 being blank; 39, side extensions in the margins of the wicket over the tablet in the position line 38 occupies when the bill is in position to be written upon, this arrangement permitting a view of line 38 upon the wider under paper, thus rendering it possible to judge as to whether or not the two running papers are maintaining their registry; 40, Fig. 2, the 100 bearings for the end journals of the spindles of the paper-rolls at the ends opposite the 105 bearings 18; 41, Fig. 5, the offset in the cam which operates the rammer-plate; 42, Fig. 6, the offset in the cam which operates the gripper, and 43, Fig. 7, a recess in the lower one of the darts adapted to receive an ordinary 110 McGill paper-fastener in such position that the folds of paper as stabbed upon the darts will also be received upon this paper-fastener.

In Fig. 3 the end door 12 is shown in dotted line as open, showing the three darts, two 115 for the top of the folds of paper and one for the bottom, the bottom one being the one to receive the paper-fastener. The length of a bill is to correspond with the vertical length of the folds. By opening the end door 12 and tearing off the unfolded record-paper the entire pile of folded papers may be removed, the darts coming with the pile. The paper-fastener may then be clenched and the darts withdrawn from the pile of paper, leaving the complete record somewhat in the form of a bound book whose leaves may be turned to expose all of the records, the back of the record-paper being the part which cannot be opened for inspection.

Were the darts not removable it would be necessary for an inspection of the leaves to take away the partition in which the darts are secured, thereby totally crippling the use

of the machine, because the machine could not be used until the door was returned, and the machine would be inoperative were the darts not removable during the examination 5 and consultation of the pile of leaves. The pile of leaves properly bound by the darts can be removed from the machine in bound form, and new darts put into the machine at once for use. In my Patent No. 518,230 it 10 would require to put the machine in condition for use, not the insertion of new darts, but that substitute fasteners be put into the pile of papers, a very much more troublesome process.

15 In my present machine a pile can be removed with its darts without removing the door, so that the use of the machine can be continued with other darts, while later the pile can be restored with its original darts 20 and the record continued where it was interrupted. Such use can be made of the machine where it is appropriated to a certain salesman in a store. When that salesman lays off for a day, his record is removed on 25 his darts and a new record started for the substitute salesman, the old record being returned and continued the next day. Another point is found in the character of the darts 30 permissible by the present arrangement. In my Patent No. 518,230 the pile is required to be pulled from the front of the stop-wires, thus preventing the use of bold retaining-bars upon the darts. In the new case the darts can have bold barbs and the removability of the darts permits the paper to be 35 stripped from their rear ends, or, otherwise expressed, permits of their being pulled out forwardly.

If the paper-fasteners be not used, still the 40 pile of paper is removable from the apparatus in convenient form for inspection, being bound, book-like, by the darts, and the pile may be easily replaced by simply reinserting the darts in the door.

45 It is to be understood that the spindle 13 has an endwise-sliding spring-pressed journal 14 in each of its ends, thus permitting the insertion of the spindle into its bearings in the casing by a square or non-tilted presentation, a matter of importance in dealing with large but short rolls of paper.

I claim as my invention—

55 1. In an autographic register, the combination, substantially as set forth, of feed mechanism to advance a strip of paper, darts beyond the feed mechanism on which the paper is to be stabbed in folds, a rammer-plate mounted for reciprocation to and from the darts, a folding-rod and operating mechanism 60 arranged to lay the paper in folds between said rammer-plate and darts, a cam holding the rammer-plate away from the darts and having a releasing point or lobe, and a spring arranged to urge the rammer-plate to the darts.

65 2. In an autographic register, the combination, substantially as set forth, with feed-

rolls, stabbing-darts, a rammer-plate, and a folding-rod arranged to lay paper in folds between the darts and rammer-plate, of a gripper 70 at the end of the path of the folding-rod, and mechanism for opening and closing the gripper to receive and grip and release the fold of paper carried down by the folding-rod.

3. In an autographic register, the combination, substantially as set forth, with feed-rolls, stabbing-darts, a rammer-plate, and a folding-rod arranged to carry a fold of paper 75 between the darts and rammer-plate, of a pair of gripping-fingers at the end of the stroke of the folding-rod, a spring tending to close said gripping-fingers, and a cam connected with one of said gripping-fingers and adapted to open and hold open the gripping-fingers and permit them in proper time to 85 close by the action of said spring.

4. In an autographic register, the combination, substantially as set forth, of a casing, paper-feeding mechanism, a rammer-plate, a folding-rod to lay the paper in folds in front 90 of the rammer-plate, a pair of stabbing-darts supported near one end of the path of said folding-rod in position to engage near the edges of the paper being dealt with, and a third stabbing-dart supported near the other 95 end of the path of said folding-rod in position to engage at the center of width of the paper being dealt with.

5. In an autographic register, the combination, substantially as set forth, of a casing, a 100 pair of feed-rolls arranged to feed forward a strip of paper with its face uppermost, a rammer-plate, a folding-rod engaging over said paper in front of said rammer-plate and arranged to carry a fold of paper down in 105 front of said rammer-plate, a pair of stabbing-darts supported in front of and near the top of the rammer-plate, and a third stabbing-dart supported in front of and near the bottom of said rammer-plate in position 110 to engage the center of width of the paper being dealt with.

6. In an autographic register, the combination, substantially as set forth, of a casing, paper-feeding rolls, darts on which the paper 115 is to stab in folds, a rammer-plate reciprocating to and from the darts, a folding-rod adapted to rise and fall between the rammer-plate and darts, a gripper to engage the base 120 of the fold of paper, a shaft turning with the paper-feeding rolls, and three independent cams upon said shaft one for operating said folding-rod and one for operating said rammer-plate and one for operating said gripper.

7. In an autographic register, the combination substantially as set forth, of a casing, a door thereto, stabbing barbed darts temporarily supported in said casing, paper-feeding mechanism to advance a web of paper into said casing toward said stabbing-darts, paper-folding mechanism to lay said paper into reverse folds in front of said stabbing-darts, and a rammer to force the folds of paper upon the stabbing-darts, whereby 130

is produced a bound book of reversely-folded leaves supported with said casing and capable of being detached in bound form therefrom.

- 5 8. In an autographic register, the combination, substantially as set forth, with a casing, paper feeding and folding mechanism, and a rammer to force the folds of paper upon darts, of a dart supported in position to have 15 the folds of paper forced upon it and provided with a holder for a clenching paper fastener.

9. In an autographic register, the combination,

substantially as set forth, with paper feeding and paper-folding mechanism and a rammer to force the folds of paper upon darts, of a dart supported in position to have 15 the folds of paper forced upon it and provided with a holder for a clenching paper fastener.

WILLIAM L. EGRY.
